NECKTIE

Clifton V. Kenney, Bayonne, N. J.

Application September 15, 1942, Serial No. 458,391

2 Claims. (Cl. 2-146)

The purpose of this invention is to facilitate tying four in hand and bow ties by providing means in the tie to expedite sliding in the collar.

The invention is a necktie having balls in the neckband thereof which contact the surface of the collar or neckband of the shirt, or collar, thereby providing a rolling action making it easy to draw the tie back and forth in the collar when tying the tie.

When tying a necktie, particularly in a laundered collar, it is necessary to draw the tie back and forth in the collar, and sometimes this is very difficult and almost tears or breaks the tie and ruffles the collar or makes it untidy.

The object of this invention is therefore, to provide means in the portion of a necktie that is placed inside of a collar whereby a rolling action, instead of a sliding action, is obtained.

Another object is to provide means for installing balls in a necktie to facilitate moving the tie in a collar.

A further object is to provide a device for holding a ball in the narrow portion of a necktie without changing the general construction of the necktie.

And a still further object is to provide a necktie having freely mounted balls therein which is of a simple and economical construction.

With these ends in view the invention embodies two concave discs having central openings with the central portions separated sufficiently to hold a ball therebetween, and prongs on one of said discs adapted to be inserted through the material of a necktie and crimped over the edge of the other disc to securely hold the discs and ball in the necktie.

Other features and advantages of the invention will appear from the following description taken in connection with the drawing, wherein—

Figure 1 is a view showing a necktie with the balls incorporated therein.

Figure 2 is a cross section through the mounting discs and necktie.

Figure 3 is a view looking toward the under side of the discs showing the prongs bent over the edges thereof.

Figure 4 is a section through the necktie and ball holding device showing an alternate design.

Figure 5 is a similar view showing another alternate design.

In the drawing the device is shown as it may be made wherein numeral 1 indicates a ball, numeral 2 an upper disc, and numeral 3, a lower disc.

The discs are concave as shown in Figure 2 55

and are positioned so that their edges engage with their central portions spaced apart so that the ball 1 may be freely held in the openings at the central parts, and these are held together by 5 prongs 4 inserted through the intermediate part 5 of a necktie and then crimped over so that both discs are held against opposite surfaces of the necktie. The ball being freely held in the openings will rotate permitting the necktie to slide freely in even a starched or laundered collar.

In the design shown in Figure 4 a ball 7 is freely held in an eyelet 8 with the central portion of the eyelet as shown at 9, concave providing contact with the ball at the edges only or the central part may be curved to the radius of the ball so that the ball will be freely held in the eyelet 8 permitting it to roll freely when the necktie is drawn back and forth in a collar. 15 20 The eyelet is provided with flanges 10 and 11 so that after the eyelet is inserted in an opening in a necktie the flanges may be crimped over to hold it in place.

In Figure 5 the holder is formed of a single disc 13 with the central part upset or drawn to form a slight flange 14 and the inner surface of this flange is curved to correspond with the radius of a ball 15, providing means for holding the ball and at the same time holding it so that it may roll freely. The disc 13 may be inserted between layers 16 and 17 forming the material of a necktie, and may be held between these layers by threads 18 as shown.

It will be noted that the size or thickness of the parts illustrated in Figures 2 to 5, are considerably exaggerated and the balls will be slightly larger than the thickness of the necktie, the other parts being smaller in proportion.

It will be understood that changes may be made in the device without departing from the spirit of the invention. One of which changes may be in the use of any number of balls mounted in combination, another may be in the use of other means for holding the balls in the mounting means, and still another may be in the use of other means for mounting the holder or mounting means in a necktie.

The construction will be readily understood from the foregoing description. In use the parts 40 45 50 may be provided as shown and described and may be inserted in or attached to a necktie by first punching holes through the tie, then inserting the balls in the holes, and then placing one disc on each side with the prongs passing through the material and then crimped over as shown

and described. With these parts in place as shown in Figure 1 the necktie may be placed in a collar and readily slid back and forth with absolute ease.

Having thus fully described the invention what I claim as new and desire to secure by Letters Patent is:

1. In a necktie, balls freely mounted in the narrow portion of the tie that is positioned inside of a collar, in use, characterized in that the mounting means comprises concave discs with central openings, and prongs extending from the edges of one of said discs adapted to be

inserted through the material of the necktie and crimped over the other of said discs.

2. As an article of manufacture, a necktie having holes therethrough, balls positioned in said holes, a concave disc positioned over the balls in the respective holes and against one side of said necktie, and another concave disc with prongs extending from the edges thereof, through the material of the necktie and over the edge 10 of the other disc, said latter disc also placed over the balls and against the opposite surface of the material of the necktie.

CLIFTON V. KENNEY.
